(57) **CLAIM**

The ornamental design for a swivel lug female sewer fitting, as shown and described.

DESCRIPTION

FIG. 1 is a top, left rear perspective view of a swivel lug female sewer fitting embodying our design;

FIG. 2 is a top, left front perspective view of the same invention in FIG. 1;

FIG. 3 is a rear side elevational view thereof;

FIG. 4 is a front side elevational view thereof;

FIG. 5 is a left side elevational view thereof;

FIG. 6 is a right side elevational view thereof;

FIG. 7 is a bottom plan view thereof; and,

FIG. 8 is a top plan view thereof.
